UNITED STATES PATENT OFFICE.

JOHN M. SCOTT, OF RACINE, WISCONSIN, ASSIGNOR TO OTTO R. BARNETT, OF CHICAGO,
ILLINOIS.

RAIL-ANCHOR.

1,143,077.

Specification of Letters Patent. Patented June 15, 1915.

Application filed November 26, 1913. Serial No. 803,191.

To all whom it may concern:

Be it known that I, JOHN M. SCOTT, a citizen of the United States, residing at Racine, in the county of Racine and State of Wisconsin, have invented certain new and useful Improvements in Rail-Anchors, of which the following is a specification.

My invention relates to devices for preventing the longitudinal creep of railway 10 rails, such devices being variously called rail anchors, rail stays or anti-creepers. In order that a device of this sort should successfully perform its intended function it must be strong, compact and so constructed that its grip upon the rail will not readily be loosened by the backward thrust of the rail which is supposed to take place immediately after the train has passed over it, or by other disturbing influences. In order 20 that the device should be salable it must consist of few parts, be easily applied to the rail, be inexpensive to manufacture both with respect to labor and material, and also be light in weight so as to minimize freight 25 charges.

The principal object of this invention is to provide a rail anchor of the wedge type, that is, a device in which the grip on the rail is produced by a wedging action between the 30 relatively movable elements of which the device is composed, which will have all of the above mentioned qualities and requisites in a maximum degree.

More particularly the purpose of the invention is to provide a rail anchor which, 35 besides being light, strong, compact and simple in its construction, will consist of elements having a wedging relation with each other, the wedging or frictionally engaged surfaces of contact of which with each other and with the rail have a considerable aggregate area and are so disposed and designed as to insure a firm and reliable grip between the device and the rail 40 and between the elements of the device when driven into operative position with each other and against the rail.

A further object is to provide the co-engaging elements of the device with a plurality of pairs of co-engaging wedging surfaces which, besides giving the relatively large area of frictional contact between the elements, operate not only to draw said elements laterally against the edges of the rail 55 base but also vertically upon the same.

The invention has for further objects such other new and improved arrangements, devices and constructions relating to rail anchors as will be hereinafter described and claimed.

The invention is illustrated, in a preferred embodiment, in the accompanying drawings wherein—

Figure 1 is a side elevation of the device shown as applied to a rail, the latter being 60 in section. Fig. 2 is a plan view of the parts shown in Fig. 1. Fig. 3 is an end elevation of the device. Fig. 4 is a plan view of the movable or wedging element of the device. Figs. 5 and 6 are views of opposite ends of 70 said element. Fig. 7 is a sectional view taken on line 7—7 of Fig. 1. Fig. 8 is a plan view of the stationary element of the device, that is, in the preferred form of my invention shown, the element which is provided with the tie abutting flange. Fig. 9 is a sectional view taken on line 9—9 of Fig. 8, and Fig. 10 is a view, in elevation, of the end of the stationary element with which the movable or wedge element engages.

Like characters of reference designate like parts in the several figures of the drawings.

Referring to the drawings, A designates a railroad rail formed with the usual base flange B, and C one of the cross ties supporting said rail.

The rail anchor, in the preferred embodiment of my invention shown, consists of a stationary element or bar D and a movable or compound wedge element E. The bar D 90 is provided at one end with a hook or jaw 10 and at the other end has a tie abutting flange 11 and is formed with a slot 12 and beyond the slot with a dovetailed rib 13. The wedge element E is formed so as to have a jaw 14 95 which engages the edge of the rail base B opposite to that engaged by the jaw 10 on bar D and is provided with a tongue 15 adapted to extend through the slot 12 in the bar D and formed with projections 16, 17 which 100 underlie and bear against portions of the under surface of the bar D on opposite sides of slot 12. The wedge element is also preferably formed with a rib 18 which with the tongue 15 provides a dovetailed slot 19 into which the dovetailed rib 13 on the bar is adapted to fit.

The device is applied to the rail by hooking the jaw 10 of the bar D over one edge of the base flange of the rail with the tie 110

abutting flange 11 bearing against the tie C, the broad flat upper face of the bar D preferably resting snugly against the under face of the rail and driving the wedge element E 5 toward the tie with its tongue 15 fitting into the slot 12 of the bar. The surfaces of contact between the stationary element D and the movable or wedge element E are preferably so disposed that when the latter element is 10 driven toward the tie it is forced inwardly against the edge of the rail base and also downwardly upon the same thereby clamping the rail vertically as well as horizontally between bar D and wedge E. The outer 15 edge 20 of the slot 12 is slightly oblique both vertically and with respect to the axis of the rail and the tongue 15 is tapered toward the tie. This causes the jaws 10 and 14 to be drawn together. The under surfaces 20 21 and 22 of the bar on opposite sides of slot 12 have a slope downwardly toward the tie abutting flange 11 and the surfaces 23, 24 of the tongue 15 are given corresponding contours. This results in drawing the 25 wedge element down upon the rail base when it is driven toward the tie. The end of the bar is preferably formed with a rounded wedge surface 25 which is frictionally engaged by a correspondingly formed surface 30 26 on the inside of the rib 18. The rib 18 is preferably rather thin so that if necessary, in order that the wedge element E should be driven into close engagement with the base flange of the rail, it will reluctantly yield or 35 bend, thus remaining in tight frictional engagement with surface 25. Its function, therefore, is not so much to effect a wedging action between the parts of the rail anchor, this function being performed by the other 40 co-acting wedge surfaces, as to increase the frictional contact between the elements of the device. It will be seen that the aggregate area of the surfaces of the two elements in frictional contact with each other 45 is considerable and when subject to corrosion by exposure to the weather, this engagement tends to become permanent. The surface 23 engages surface 21. The surface 24 engages surface 22. The surface 26 engages the 50 surface 25, while the flat upper surface of bar D tightly engages the flat under surface of the rail. Moreover, these pairs of co-acting wedge surfaces are not in the same plane, which circumstance increases the grip between the elements. 55

While I have described my invention in a preferred embodiment, it will be understood that modifications might be made without departure from the principles of the invention. The portion of the device, specifically the part of the bar D, which bears against the tie C is referred to in the claims as "tie abutting" element or flange. Obviously, however, the device might be positioned against a stationary or relatively sta-

tionary element of the roadbed other than one of the cross ties ordinarily used for supporting railway rails.

I claim:

1. A rail anchor comprising two relatively 70 movable elements which are provided with rail engaging members adapted to engage the base flange of a rail on opposite sides thereof, one of which is provided with a tie abutting portion; said elements being formed 75 each with a slot and with a tongue adapted to fit into the slot of the other element and with a wedge surface adapted to engage a wedge surface on the other element.

2. A rail anchor comprising two relatively 80 movable elements which are provided with rail engaging members adapted to engage the base flange of a rail on opposite sides thereof, one of which is provided with a tie abutting portion; said elements being 85 formed each with a slot and with a tongue adapted to fit into the slot of the other element, and with a plurality of wedge faces adapted to engage wedge faces on the other element. 90

3. A rail anchor comprising two relatively 95 movable elements which are provided with rail engaging members adapted to engage the base flange of a rail on opposite sides thereof, one of which is provided with a tie abutting portion; said elements being formed 100 each with a slot and with a tongue adapted to fit into the slot of the other element, said tongues and slots being formed so as to provide mutually overlapping parts. 100

4. A rail anchor comprising two relatively 105 movable elements which are provided with rail engaging members adapted to engage the base flange of a rail on opposite sides thereof, one of which is provided with a tie abutting member; one of said elements being formed with a slot extending 110 there-through and with a dovetailed rib, and the other with a tongue extending through said slot and engaging the under side of the first 115 named element and with a dovetailed groove adapted to receive the dovetailed rib of said first named element. 115

5. A rail anchor comprising two relatively 120 movable elements which are provided with rail engaging members adapted to engage the base flange of a rail on opposite sides thereof, one of which is provided with a tie abutting member; one of said elements being formed with a slot extending 125 there-through and with a dovetailed rib, and the other with a tongue extending through said slot and engaging the under side of the first named element and with a dovetailed groove adapted to receive the dovetailed rib of said first named element, said elements being formed with a plurality of pairs of co-acting wedge faces disposed so that when one of said elements is moved with respect to the other in one direction one of said rail engag- 130

ing members is drawn down upon the rail brace and toward the other rail engaging member.

6. A rail anchor comprising two co-engaging relatively movable elements provided with co-acting wedge faces, one of said elements being formed with a part overlapping and frictionally engaging the other which is adapted to yield, for the purpose described.

7. A rail anchor comprising two elements, one of which is formed with a slot and the other with a tongue adapted to fit into said slot and underlie a portion of the first named element; one of said elements being provided with a part overlapping and frictionally engaging the other element which is adapted to yield, for the purpose described.

8. A rail anchor comprising two elements, one of which is formed with a slot and the other with a tongue adapted to fit into said slot, one of said elements being provided with a part overlapping and frictionally engaging the other element which is adapted to yield, for the purpose described.

9. In a rail anchor the combination with a bar provided with a tie abutting flange and formed at one end with a jaw and at the other with a slot, of a wedge element having a jaw, and a tongue adapted to extend into said slot and underlie a portion of said bar adjacent said slot and beneath the rail flange.

10. In a rail anchor the combination with a bar provided with a tie abutting flange and formed at one end with a jaw and at the other with a slot, of a wedge element having a jaw, and a tongue adapted to extend into said slot and underlie a portion of said bar adjacent said slot, the tongue and slotted portion of the bar being provided with a plurality of pairs of wedging surfaces which operate, when the wedge element is driven toward the tie against which the device bears to draw said wedge element down against the base flange of the rail and laterally against the edge of the same.

11. In a rail anchor, the combination with a bar provided with a tie abutting flange and formed at one end with a jaw and at the other with a slot and with a dovetailed

rib, of a wedge element having a jaw, a tongue extending through said slot and a dovetailed groove adapted to receive the dovetailed rib on the bar.

12. In a rail anchor, the combination with a bar provided with a tie abutting flange and formed at one end with a jaw and at the other with a slot and with a dovetailed rib, of a wedge element having a jaw, a tongue extending through said slot and a dovetailed groove adapted to receive the dovetailed rib on the bar, said elements being formed with a plurality of pairs of co-acting wedge faces which operate, when the wedge element is driven toward the tie against which the device bears, to draw said element down upon the rail base and laterally against the edge thereof.

13. In a rail anchor, the combination with a bar provided with a tie abutting flange and formed at one end with a jaw and at the other with a slot, of a wedging element having a jaw, a wedging tongue adapted to extend through said slot, and a bendable rib having a wedging bearing on the end of said bar.

14. A rail anchor comprising two relatively movable elements which are provided with rail engaging members adapted to engage the base flange of a rail on opposite sides thereof, one of which is provided with a tie abutting portion; each element being formed with a dove-tailed tongue which forms one side of a dove-tailed slot for the corresponding tongue of the other element.

15. A rail anchor comprising two relatively movable elements which are provided with rail engaging members adapted to engage the base flange of a rail on opposite sides thereof, one of which is provided with a tie abutting portion; each element being formed with a dove-tailed, tapering tongue which forms one side of a dove-tailed, tapering slot for the corresponding tongue of the other element.
